UNITED STATES PATENT OFFICE.

EUGENE LEVAY, OF NEW YORK, N. Y.

HOB OF A QUOIT GAME.

Application filed July 13, 1925. Serial No. 43,279.

My invention relates to certain improvements in a quoit game, or game played with a hob and rings.

One object of the invention is to construct the hob so that it can be rocked in any direction while the rings are being tossed at it.

A further object of the invention is to construct the hob so that it will be comparatively light, yet substantial.

The invention also contemplates the provision of a game of the stated type adapted for use by bathers while in the water.

In the accompanying drawings: Figure 1 is a perspective view of my improved hob; Fig. 2 is a perspective view of one of the rings used in playing the game, and Fig. 3 is a sectional elevation of my improved hob.

The hob has a body portion 1, which consists of a hemispherical base 2 and a disk 3 to which the base is attached. The disk is preferably made of wood, and the base is made of pressed fibrous material, such as wood pulp. In the base is a weight 4, which consists of an iron disk having a socket 5 for the end of the center post 6, which extends through an opening in the disk 3. This post is secured to the weight 4 by a screw 7, or other fastening.

The disk 3, in the present instance, has four radial recesses 8 to receive the curved projections 9, which form pegs, and which are, preferably, attached to the post at their lower ends, as well as being secured to the disks.

The central post 6 has a ball 10 at its upper end, and the curved projections terminate in the form of anchor flukes 11. There are four projections 9 illustrated, but the number may be varied, as desired.

The post and the curved projections are made to represent an anchor, in the present instance. The post and each of the projections are numbered, as indicated in Fig. 1.

The game is played by tossing the rings (illustrated in Fig. 2) towards the hob and the count is dependent upon the particular ring play made.

While the hob as well as the rings may be made of any suitable material, a particular-

ly desirable result is obtained by so forming the parts that they will float in water, thereby making this game available to bathers while in the water.

It will be apparent that the device with the hob weighted as previously stated will tend to assume the normal upright position in the water, and in use behaves in substantially the same manner as when the game is played on land.

I claim:

1. The combination in a hob of a quoit game; of a body having a substantially hemispherical base; a weight in the base; a central projection secured to the weight and extending above the body; a series of curved projections extending from the base at the post, the post being of greater length than the projections.

2. The combination in a hob of a quoit game, of a hollow body having a substantially hemispherical base; a disk secured thereto; a weight at the bottom of the body; and a post secured to the weight and extending through the disk.

3. The combination in a hob of a quoit game, of a hollow body having a hemispherical base and a disk; a post extending through the disk, said disk having radial recesses therein and projections having their lower ends in the recesses; and a weight in the base of the body portion.

4. The combination in a hob of a quoit game, of a hollow body portion having a substantially hemispherical base of pressed fibrous material and a wooden disk to which the base is attached; a weight in the bottom of the base; a post attached to the weight and extending through the disk, said disk having a series of recesses radiating from the post; and a series of curved projections secured to the recesses of the disk and projecting to form pegs.

5. The combination in a hob of a quoit game, of a water-buoyant body having a substantially hemispherical base, a weight in the bottom of the body causing the latter to assume a normal upright position in water, and projections extending upwardly from the said body when the latter is in said normal position.

EUGENE LEVAY.
